United States Patent Office.

ZACCHEUS B. SHANNON, OF PORT WASHINGTON, OHIO.

Letters Patent No. 61,882, dated February 5, 1867.

IMPROVEMENT IN ROTARY PUMPS.

The Schedule referred to in these Letters Patent and making part of the same.

TO ALL WHOM IT MAY CONCERN:

Be it known that I, ZACCHEUS B. SHANNON, of Tuscarawas county, in the State of Ohio, have invented certain new and useful improvements in the Mode of Raising Water from Wells, Reservoirs, &c.; and I do hereby declare that the following is a full and exact description thereof, reference being had to the annexed drawings, and to the letters of reference thereon marked. In the drawings—

Figure 1 is a plan view.

Figure 2 is a section on line $z z$, fig. 1.

Figure 3 is a section on line $y y$, fig. 1.

To enable those skilled in the art to make and use my invention, I will describe its construction and operation.

My invention is intended to be used for the purpose of raising water from wells or other places for domestic and other purposes. My improved water raiser may be operated by any suitable power, hand-crank, steam, horse, or water. The drawings represent it as operated by a horizontal water-wheel.

A is what I term the elevator, and is a cylindrical wheel revolving in the penstock or discharge tube. It is composed of two metallic disks, (from three to twelve or more inches in diameter,) the upper one made fast to the shaft, which extends to the top of the well. The space between the two disks is about equal to half their diameter. The two disks are connected together by curved flanges or buckets, (dotted lines, fig. 1,) so as to form a hollow around the shaft, with four or more issues, somewhat like a turbine wheel. D is the penstock, and is a square tube, of a diameter somewhat greater than that of the elevator. This penstock is set in the bottom of the well or reservoir C, where the water is to be raised, and is open at its bottom so that the water can freely enter it. H are beaters in the penstock. G is the conductor for leading the water from the $\dots$ to the $\dots$, or other place.

In operating my invention, power is communicated to the shaft of the elevator by means of a crank or any similar device for applying power, and by means of a belt running from the shaft of the water-wheel B, which is driven by the water from the forebay or other suitable means, which causes the elevator to revolve rapidly. The elevator being just below the surface of the water, as it revolves it vents or throws out the water it contains up in the penstock, and thus creates a vacuum within itself, into which the water in the reservoir rapidly rushes. In this manner I can raise water to any reasonable height required. It must be borne in mind that there must be from two to four beaters or check-paddles, H, to prevent the water in the penstock from running around with the elevator. It will be seen that the opening in the bottom of the penstock contains the same number of square inches that is contained in the issues of the ventilator or elevator. The penstock is to be set on four feet, from one to four inches high, according to the quantity of water to be raised, which will let it pass freely into the elevator. The lower end of the shaft of the elevator rests in a step set in the bottom of the reservoir.

Having thus fully described my invention, what I claim as new, and desire to secure by Letters Patent, is—

The combination and arrangement of the elevator A, penstock D, and check-paddles H, constructed and operating, substantially as described and for the purposes set forth.

ZACCHEUS B. SHANNON.
